Primary Examiner—Robert M. Spear*Assistant Examiner*—Mary Ann Calabrese(57) **CLAIM**

The ornamental design for the set of alphabetic labels, as shown and described.

DESCRIPTION

These alphabetic labels can be used as end tab labels for end tab folder pockets or applied to other labeling purposes.

FIG. 1 is a front view of the set of alphabetic labels showing my new design; and,

FIG. 2 is a front view of an alternate embodiment of my set of alphabetic labels.
